PISTON

Macy O. Teetor, Newcastle, Ind., assignor to
The Perfect Circle Company, Hagerstown, Ind.,
a Corporation of Indiana

Application January 24, 1931. Serial No. 510,900

6 Claims. (Cl. 309—11)

My invention relates to pistons and more particularly to those adapted for use in internal combustion engines and the like.

The principal object of my invention is to provide a piston having minimum and uniformity of clearance in the cylinder throughout all speed and temperature ranges of the engine without risk of seizing or binding or of undue wear taking place at any point of the piston or cylinder, while at the same time "blow-by", oil pumping and piston slap are substantially eliminated.

Another object of the invention is to provide a piston which will accomplish the above while at the same time it will be simple in design, easily cast and cheap to manufacture.

These and further objects of my invention will appear from the following specification, reference being had to the accompanying drawing, and the novel means by which said objects are effectuated will be definitely pointed out in the claims.

In the drawing:

Figure 1 is a longitudinal section taken through a piston embodying my invention, the section being taken on the line 1—1 of Fig. 2;

Fig. 2 is a longitudinal section taken generally at 90° to Fig. 1, the section being taken on the line 2—2 of Fig. 3;

Fig. 3 is a cross section through the piston, being taken on the line 3—3 of Fig. 2; and

Fig. 4 is a cross section taken on the line 4—4 of Fig. 1.

My improved piston, which is made of metal having a lower specific gravity than iron, such as an aluminum alloy, includes a skirt 6 and a head 5, the latter being provided with grooves for receiving piston rings. A circumferential slot 7 separates the top of the skirt from the depending wall of the head. The skirt is provided with a vertical slot 8 which extends from end to end of the skirt.

The head and skirt are connected together interiorly by two parallel struts 9 which carry the piston pin bosses 10, projecting in opposite directions and in alignment with enlarged openings 11 in the skirt. Each strut 9, which is cast integrally with the head and skirt has the general form of an inverted T and includes a vertical arm 12 depending from the top of the piston, a laterally projecting arm 13 integrally connected to the skirt opposite the slot 8, and an oppositely extending arm 14 integrally united at its outer end to one edge of a vertical web 15 carried by the skirt, there being two aligned webs 15, one for

each strut. The arms 13 and 14 constitute, in effect, cross members.

The webs 15 are integrally united at their upper and lower ends respectively to circular ribs 17 and 18 on the skirt. When the piston is first cast, the webs 15 form an undivided piece, but when the slot 8 is cut into the skirt the slot 19 between the webs is cut by the same tool to form the two disconnected webs.

It will be observed that the arms 12 of the struts are spaced from the depending circular wall of the head, that the arms 14 are narrow (vertically) and connected to the long vertical webs 15, intermediate the upper and lower ends of the latter, that the bosses 10 are independent of the skirt and that the arms 13 are relatively wider and hence less flexible laterally than the arms 14. The arms 13 are preferably not joined directly to the circular ribs 17 and 18 on the skirt.

In operation, the head of the piston is always at a higher temperature than the skirt but, due to the circumferential slot 7 between the head and skirt, the former may expand more than the latter. The larger portion of the heat in the head is conducted directly through the piston rings to the water jacketed walls of the cylinder, but a certain portion of this heat flows downward through the flexible struts 9 to the wrist pin bosses 10 and the skirt. The rise in temperature of the skirt tends to cause a radial expansion of the same, but owing to the vertical slot 8 in the skirt it may yield circumferentially to accommodate itself to the cylinder. The expansion of the head on the diameter in the plane of the slot 8 (i. e., the plane on which Fig. 1 is taken) does not tend to distort the skirt. However, expansion on the diameter at right angles to the slot 8 (i. e. in the plane of the cross section of Fig. 2) moves the upper ends of the struts 9 apart, and this movement would distort the skirt if the struts 9 were not flexible to permit them to bend slightly and thus accommodate this movement of the upper ends of the struts. It will also be observed that as the slot 8 closes when the metal of the skirt expands, this movement is permitted by the flexibility of the arms 13 and 14.

The webs are arranged at right angles to the struts and the arms 14 of the struts are united to the webs at the outer edges (i. e., the edges opposite the slot 19) of the webs and intermediate the upper and lower ends of the latter. Due to this arrangement, when the arms 13 and 14 expand in the direction of their length cross-wise of the piston, the vertical webs bend between their upper and lower ends and probably twist

slightly out of their plane, so that the expansion of these arms is not transmitted to the skirt. Were the angular relation between each web and strut greater than 90°, then when the arms 5 13 and 14 expanded lengthwise they would exert a component force on the web in the plane of the latter and tend to distort the skirt. This distortion would be aggravated further by the tendency of the web to expand widthwise in its plane due 10 to the increase in temperature.

It will now be apparent that a piston embodying my invention is admirably adapted to accomplish the objects first above stated. The expansion of the head will not distort the skirt, which 15 is permitted to maintain a close working fit throughout its circumference with the cylinder at all temperatures and speeds without risk of sticking or undue wear taking place at any point of the piston or cylinder. "Blow-by", oil pumping 20 and piston slap are practically eliminated. The piston is simple in design, easily cast and may be finished at a low cost.

I claim:

1. In a piston of the class described, a skirt and 25 a head with a circumscribing slot between the same, the skirt having a longitudinal slot, vertical webs connected to said skirt only at their upper and lower ends, and flexible struts depending from said head and each including a laterally 30 projecting arm connected at its outer end to one edge of its respective web and forming a right angle with the web.

2. In a piston of the class described, a skirt and 35 a head with a circumscribing slot between the same, the skirt having a longitudinal slot, vertical webs adjacent either side of said longitudinal slot and connected to the skirt only at their upper and lower ends, and flexible struts depending from the head and connected to said 40

webs intermediate the ends of the latter, the webs being flexible and arranged at right angles to the struts.

3. In a piston of the class described, a skirt and a head with a circumscribing slot between 80 the same, the skirt having a longitudinal slot, vertical webs immediately adjacent either side of said longitudinal slot and connected to said skirt only at their upper and lower ends, flexible struts depending from said head and connected to the side of the skirt opposite said longitudinal slot and also connected to said flexible webs.

4. In a piston of the class described, a skirt and a head with a circumscribing slot between 90 the same, the skirt being provided with a longitudinal slot, flexible members carried by said skirt adjacent said longitudinal slot and separated by a coinciding slot, and struts depending from said head and connected to said flexible members and to the opposite side of the piston.

5. In a piston of the class described, a skirt and a head, the skirt and head being separated by a circumferential slot, struts depending from said head and carrying the piston pin bosses independently of the skirt, adjacent flexible vertical 100 webs, each connected only at its upper and lower ends to one side of the skirt, arms connecting only the central portions of said vertical webs to said struts, and arms directly connecting the other side of the skirt to said struts.

6. In a piston of the class described a skirt and a head, the skirt and head being separated by a circumferential slot, struts depending from said head, adjacent vertical webs arranged at right angles to said struts and each web connected only 110 at its upper and lower ends to said skirt, and arms connected only to the central portions of said webs and to said struts.
